SYRINGE

Clarence E. Leonard and Grace E. Leonard,
Bethlehem, Pa.

Application May 25, 1935, Serial No. 23,387

9 Claims. (Cl. 128—232)

Our invention relates to a new and useful improvement in a vaginal syringe, and has for its object the provision of a syringe of this type which will be economical and highly efficient in use, durable, easily and quickly operated, and possessed of features productive of the maximum of comfort when in use.

Another object of the invention is the provision of a vaginal syringe whereby the flushing liquid may be delivered through the delivery conduit and at the same time carried away through the outlet conduit.

Another object of the invention is the provision of a syringe of this type in which the fluid delivered through the delivery conduit may be maintained until a pre-determined pressure is reached, whereupon it may be permitted to escape through the outlet conduit.

Another object of the invention is the provision in a syringe of this type of a longitudinally movable delivery pipe or nozzle which may be adjusted to various lengths.

Another object of the invention is the provision of a syringe of this type having a telescoping delivery pipe or nozzle so that it may be collapsed, and thus a device provided which will occupy a minimum amount of space when stored away.

Another object of the invention is the provision of a syringe of this type having simple and effective means for maintaining the outlet pipe or nozzle surrounded by a quantity of sterilizing medium when not in use.

Other objects will appear hereinafter.

The invention consists in the combination and arrangement of parts hereinafter described and claimed.

The invention will be best understood by referring to the accompanying drawing which forms a part of this specification, and in which,

Fig. 1 is a central sectional view of the invention.

Fig. 2 is a sectional view taken on line 2—2 of Fig. 1.

Fig. 3 is a fragmentary sectional view of another form of the invention.

Fig. 4 is a fragmentary sectional view of the form shown in Fig. 3 with the bulb collapsed.

Fig. 5 is a central sectional view of another form of the invention, with the delivery pipe or nozzle in outwardly extended position.

Fig. 6 is a fragmentary sectional view of the form shown in Fig. 5 with the nozzle collapsed.

In the form shown in Fig. 1, we have provided a collapsible bulb 12, formed from rubber or the

like, and extended centrally through which is a rigid tube 13. Projecting outwardly from one end of the tube 13, so as to extend exterior of the bulb 12, is a nipple 14, on to which is threaded the delivery pipe or nozzle 15. The interior of the nipple 14 is in communication with the interior of the bulb 12 through the passages 16. Passages 17 extending through the head 18 communicate with the interior of the tube 13.

The construction is such that when the bulb 12 is filled with liquid, and the delivery pipe 15 placed in position for use, a squeezing of the bulb will eject the liquid outwardly through the passage 16, and through the delivery pipe or nozzle 15.

The face 19 of the bulb will engage against the body sufficiently to effect a sealing connection, and the liquid delivered through the nozzle or delivery pipe 15, after flushing, will flow through the passages 17, and outwardly through the outlet pipe 13. Thus there is provided a simple and effective means for maintaining a constant flow of flushing liquid by the use of a syringe of this type.

In Fig. 3, we have shown a bulb 12, with a tube 13' extended centrally therethrough, and provided at one end with the head 18'. This tube 13' is formed from hard rubber or the like, sufficiently stable to retain its shape. The head 18', however, is formed from flexible rubber and imbedded at one end in the head 18' are the rigid arms 20 having the curved ends 22 and extended angularly to the tube 13', which forms the axis of the bulb 12. Inwardly of one end of the head 18', and projecting outwardly therefrom, is the delivery tube or nozzle 23, communicating through passage 24, with the interior of the bulb 12. The face 19 of the bulb will be pressed against the body to effect a sealing connection. When the bulb 12 is squeezed, the liquid therein will be expelled through the passages 24 outwardly through the delivery pipe 23. As the liquid is delivered through the delivery pipe 23 and the face 19 held in sealing connection against the body, it is obvious that a pressure will be built up in the vagina. This will continue until the bulb 12 is pressed inwardly sufficiently to engage the arms 20, and rock them inwardly on the point 23', which is formed from hard rubber. This will cause the portion 25 to be stretched outwardly away from the reduced portion 26, so that the liquid delivered through the nozzle or pipe 23 may pass into the outlet 55

pipe or tube 13'. In this way, we have provided a syringe whereby a constant flow, inwardly and outwardly, of the liquid will take place after a pre-determined amount of liquid has been delivered. Thus there is afforded a means for building up a pressure before the escape of liquid takes place.

The position of the various parts in the escap-
ing position is clearly shown in Fig. 4.

10 In Fig. 5 and Fig. 6, we have shown a bulb pro-
vided at one end, projecting outwardly from the
face 19', with a tapered neck 28, which when
in use, is adapted to extend between the vulva.
Projecting through the bulb and extending out-
wardly of the neck 28, is an outlet tube 29. This
tube 29 is formed of hard material and is pro-
vided, at the end which projects through the wall
30 of the bulb, with a flexible portion 31, in
which are imbedded the ends of the arms 20'
20 having the curved ends 22'. Surrounding the
outlet tube 29 is a ring 32 of a hard material,
which serves as a fulcrum for the arms 20'. Pro-
jecting inwardly from the flexible portion is a
bead 33. Slidably mounted in the tube 29 is the
25 nozzle or outlet delivery pipe 34, which is formed
from hard rubber or the like. In the periphery
of this tube 34 are formed grooves 35. The dis-
charge opening 36 in the outlet pipe or nozzle
34 is threaded to receive the threaded stud of
30 the cup shaped cap 38, which is provided on
the base with the peripheral flange 39. Resting
on the inner surface of the base of the cap is a
washer or gasket 40. The nozzle or outlet pipe
34 may be telescoped within the tube 29, as shown
35 in Fig. 6, and when in this position the cap 38
may be secured on the nozzle 34 by means of
the threaded stud 37, so that the gasket 40 will
bear against the end of the nozzle or pipe 34.
The cup will also engage the face 19' in sealing
40 connection. When in this position, the stud 37
will be threaded into the threaded end of the
small delivery tube 41. This tube 41 extends
centrally of the tube 39, and is formed with the
T-branches 42 at its inner end, which projects
45 through the tube 29, and form a means for com-
municating the interior of the outlet pipe or
nozzle 34 with the interior of the bulb 27. This
tube 41 slidably projects through the cap 43
which serves as a closure for the rear end of the
50 nozzle or delivery pipe 34. The rear end of this
delivery pipe is provided with grooves 44 formed
on its periphery. When in the collapsed pos-
ition shown in Fig. 6, the tube 29 may be filled
55 with suitable sterilizing material, and this ster-
ilizing material will be in contact with the en-
tire surface of the pipe 34. When the tube 29 is
filled with the sterilizing material, a plug may
be threaded into threaded portion 45 of the tube
29, and serve to close this tube.

60 When it is desired to use the device, the cap
38 may be threaded outwardly until the stud 37
disengages from the tube 41, whereupon by grip-
ping the flange 39, the entire structure may be
pulled outwardly and the cap then removed from
65 the delivery pipe or nozzle 34. In this act or
movement, the flexible end 31 of the tube 29 will
engage in the grooves 35, or the nozzle may be
pulled outwardly so that the bead 33 engages in
these grooves. When the bulb 27 is filled with
70 cleansing liquid, a squeezing of the bulb will
force the liquid through the T-branches 42, and
through the tube 41, into the delivery pipe or
nozzle 34. The face 19' of the wall 30, will be
75 of course held against the body in sealed con-
nection so that a pressure will be built up until

the arms 20' are rocked inwardly at their free
ends to raise the flexible portion outwardly from
the periphery of the nozzle 34, and permit the
liquid to escape, by means of the grooves 44, into
the interior of the outlet tube 29. It is believed 5
obvious that, if desired, a suitable outlet deliv-
ery pipe may be connected to the threaded por-
tion 45, for conducting the escaping fluid to any
desired location or receptacle.

The advantages obtained from the use of the 10
device shown in Fig. 1, and Fig. 3, are present in
the structure illustrated in Fig. 5, and Fig. 6.
But in the structure illustrated in Fig. 5 and Fig.
6, the delivery pipe or nozzle will be telescoped 15
so that the device may be collapsed into very
compact form, thus affording a device which will
occupy a minimum amount of space when stored
away.

The facility of maintaining the nozzle sur-
rounded by a sterilizing medium when not in use, 20
which is present in the form shown in Fig. 5, is
of course not present in the other forms as shown.

The tubes 13, 13' and 29, are secured to the
bulb preferably by being vulcanized thereto.

It is thus seen that we have provided a syringe 25
of this kind which is capable of functioning to
a maximum degree of efficiency while at the
same time the operation of the device is very
simple and easily effected.

While we have illustrated and described the 30
preferred forms of construction, we do not wish to
limit ourselves to the precise details of construc-
tion shown, but desire to avail ourselves of such
variations and modifications as come within the
scope of the appended claims. 35

Having thus described our invention, what we
claim as new and desirable to secure by Letters
Patent is:

1. A syringe of the class described comprising: 40
a collapsible bulb; an outlet tube projecting
axially through said bulb; a delivery pipe mount-
ed on said tube adjacent one end thereof and
non-communicating therewith, there being pas-
sages formed for communicating said delivery
pipe with the interior of said bulb; a flexible por-
tion on one end of said outlet tube embracing
45 said delivery pipe and adapted when in embrac-
ing relation relatively thereto, for sealing said
end of said tube around said pipe, and adapted
upon distention for permitting passage of liquids 50
surrounding said pipe into said tube; and means
interior of said bulb and engageable thereby upon
collapsing thereof for distending said flexible
portion. 55

2. A syringe of the class described comprising: 55
a flexible bulb; an outlet pipe projecting
axially through said bulb; a delivery pipe slid-
ably mounted in said outlet pipe and non-com-
municating with the interior thereof; means for
establishing communication of the interior of 60
said delivery pipe with the interior of said bulb;
a cap for the outer end of said delivery pipe; and
means on said cap cooperating with the end of
said establishing means for retaining said cap
in sealing relation against one face of said bulb 65
and against the end of said delivery pipe.

3. A syringe of the class described comprising: 70
a collapsible bulb; an outlet pipe projected
axially through said bulb; a delivery pipe slidably
mounted in said outlet pipe and telescoping
therewith, and non-communicating therewith;
means for establishing communication of said 75
delivery pipe with the interior of said bulb; a
flexible portion on one end of said outlet pipe
embracing said delivery pipe, and normally in

snug sealing engagement therewith; and means connected to said flexible portion and projecting inwardly of said bulb, and adapted upon rocking inwardly, for distending said flexible portion out 5 of engagement with the periphery of said delivery pipe.

4. A syringe of the class described comprising: a collapsible bulb; an outlet pipe projected axially through said bulb; a delivery pipe slidably mounted in said outlet pipe and telescoping therewith, and non-communicating therewith; means for establishing communication of said delivery pipe with the interior of said bulb; a flexible portion on one end of said outlet pipe embracing said delivery pipe, and normally in snug sealing engagement therewith; and means connected to said flexible portion and projecting inwardly of said bulb, and adapted upon rocking inwardly, for distending said flexible portion out 10 of engagement with the periphery of said delivery pipe, the rear end of said delivery pipe having grooves formed therein to provide passages for the flow of liquid from around said delivery pipe into the interior of said outlet pipe.

25 5. A syringe of the class described comprising: a collapsible bulb; an outlet pipe projected axially through said bulb; a delivery pipe slidably mounted in said outlet pipe and telescoping therewith, and non-communicating therewith; means for establishing communication of said delivery pipe with the interior of said bulb; a flexible portion on one end of said outlet pipe embracing said delivery pipe, and normally in snug sealing engagement therewith; and means 30 connected to said flexible portion and projecting inwardly of said bulb, and adapted upon rocking inwardly, for distending said flexible portion out of engagement with the periphery of said delivery pipe, the rear end of said delivery pipe having grooves formed therein to provide passages for the flow of liquid from around said delivery pipe into the interior of said outlet pipe.

35 45 40 45 50 55 55

6. A syringe of the class described comprising: a collapsible bulb; an outlet pipe projected axially through said bulb; a neck on one wall of said bulb projected outwardly therefrom and engaging the periphery of said outlet pipe; a delivery pipe slidably mounted in said outlet pipe and non-communicating thereto; and means for establishing communication of said delivery pipe with the interior of said bulb, and maintaining said communication regardless of the position of longitudinal movement of said delivery pipe.

7. A syringe of the class described comprising: a collapsible bulb; an outlet pipe projected axially through said bulb; a delivery pipe slidably mounted in said outlet pipe and non-communicating therewith; a tube centrally mounted in said outlet pipe and communicating at one end with the interior of said bulb; a cap on the inner end of said delivery pipe, said centrally positioned tube projecting through said cap and establishing communication of the interior of said bulb with the 10 interior of said delivery pipe.

8. A syringe of the class described comprising: a collapsible bulb; an outlet pipe projected axially through said bulb; a delivery pipe slidably mounted in said outlet pipe and non-communicating therewith; a tube centrally mounted in said outlet pipe and communicating at one end with the interior of said bulb; a cap on the inner end of said delivery pipe, said centrally positioned tube projecting through said cap and establishing communication of the interior of said bulb with the interior of said delivery pipe, the end of said centrally positioned tube being internally threaded, and the outer end of said delivery pipe being internally threaded; a cup-shaped cap; a stud 25 projecting centrally upwardly from the base of said cup shaped cap, said stud being threadable into the threaded ends of said delivery pipe and said centrally positioned tube, and securing the open end of said cap in sealing engagement with 30 one face of said bulb, and the base of said cap in sealing engagement with the end of said delivery pipe.

9. A syringe of the class described comprising: a collapsible bulb; an outlet pipe projected axially through said bulb; a delivery pipe slidably mounted in said outlet pipe and non-communicating therewith; a tube centrally mounted in said outlet pipe and communicating at one end with the interior of said bulb; a cap on the inner end of said delivery pipe, said centrally positioned tube projecting through said cap and establishing communication of the interior of said bulb with the interior of said delivery pipe, the end of said centrally positioned tube being internally threaded 40 and the outer end of said delivery pipe being internally threaded; a cup shaped cap; a stud projecting centrally upwardly from the base of said cup shaped cap, said stud being threadable into the threaded ends of said delivery pipe and said centrally positioned tube, and securing the open end of said cap in sealing engagement with one face of said bulb, and the base of said cap in sealing engagement with the end of said delivery pipe, the end of said outlet tube opposite the 45 location of said stud bearing cap being internally threaded for the reception of a closure.
